O. GRUNDMANN.

SWIMMING DEVICE.

APPLICATION FILED OCT. 1, 1920.

1,374,077.

Patented Apr. 5, 1921.

Inventor
Otto Grundmann
By his Attorney
Max. Ordemann

UNITED STATES PATENT OFFICE.

OTTO GRUNDMANN, OF JERSEY CITY, NEW JERSEY.

SWIMMING DEVICE.

1,374,077.

Specification of Letters Patent.

Patented Apr. 5, 1921.

Application filed October 1, 1920. Serial No. 414,062.

To all whom it may concern:

Be it known that I, OTTO GRUNDMANN, a citizen of the United States of America, residing at Jersey City, in the county of Hudson and State of New Jersey, have invented certain new and useful Improvements in Swimming Devices, of which the following is a specification.

The present invention relates to swimming devices and has for its object to provide an improvement of the construction described and shown in my U. S. Patent #1,340,892, dated May 25th, 1920.

The invention consists in the novel construction, arrangement and combination of parts as will be hereinafter fully described and defined in the appended claims.

In the accompanying drawing in which similar reference characters denote corresponding parts, Figure 1 is a side elevation of my device showing its attachment to a shoe; Fig. 2 is a perspective view of the device; Fig. 3 is a section on line 3—3 of Fig. 1, Fig. 3^a is a front view of a detail; and Fig. 4 is a perspective view of a somewhat modified form of the device.

My device is adapted to be used principally in connection with a shoe such as originally used for bathing but may with slight modifications be made applicable to the hands.

When used in connection with shoes, the latter, as will be hereinafter described, are equipped with means for the attachment of the device.

The device proper, of which one is used for each foot, consists of a paddle shaped rigid blade *a* which is so dimensioned that it will, when applied to the foot of the swimmer, considerably enlarge the area of the foot. The blade *a* is so shaped as to present a broad surface over the front of the foot, considerably larger in area than that of the latter, and a somewhat narrower surface at its rear.

The blade may be curved as shown in the drawing and at its rear end recessed, as at *a'* (Fig. 2) or as at *e'* (Fig. 4) to enable its being slipped around the lower front part of the leg above the ankle.

Projecting downwardly from the rear part of the plate are two rigid members *b*,

one on each side of the mouth or recess *a'*. The members are suitably fixed to the plate *a* and have each a cross opening or eye *b'*. 55 A screw bolt *c* formed with a rigid disk shaped base *c'* is adapted to be fixed to each side of the shoe *s* below the ankle. The base may be perforated as at *c''* to permit its attachment to the shoe by stitches or otherwise. The screw bolts *c* when applied to the shoe, will project laterally and are adapted to pass through the openings or eyelets *b'* of the members *b*. The latter are tightened in position by means of thumb nuts *d* working on said bolts. 60 65

The blade *a* may be steadied in position by additional screws *c''* fixed to the toe portion of the shoe in a similar manner to the bolts *c* and which are adapted to pass through either one of a series of openings *a''* provided in the front part of the blade. 70

The modified blade *e* shown in Fig. 4 is identical in construction with that shown in Fig. 2, except that the mouth or recess *e'* is elongated to permit the blade to be applied to the foot in a somewhat inclined position either parallel to or bearing on the upper part of the shoe. 75

What I claim and desire to secure by Letters Patent is:

1. A swimming device, comprising a rigid blade having at its rear a recess or mouth to engage around the lower part of the leg of the swimmer, rigid members projecting downwardly from said blade and means adapted to be fixed to a shoe and to engage said members so as to hold the said blade in position. 85

2. A swimming device comprising a recessed rigid blade adapted to engage around the lower part of the leg of the swimmer, rigid perforated members projecting downwardly from said blade, and means adapted to be fixed to a shoe so as to pass through the perforations of said members for holding said blade in position. 90 95

In testimony whereof I affix my signature in presence of two witnesses.

OTTO GRUNDMANN.

Witnesses:

MAX D. ORDMANN,
JOSEPH F. McMAHON.
